UNITED STATES PATENT OFFICE.

HERMANN HILL, OF DUNKIRK, NEW YORK, ASSIGNEE TO JOHN A. DIENNER, OF EVANSTON, ILLINOIS, AND ALEXANDER C. MABEE, OF ELMHURST, ILLINOIS.

RAIL ANCHOR.

Application filed March 20, 1925. Serial No. 16,905.

My invention relates to rail anchors of the class disclosed and broadly claimed in Patent No. 1,505,090, of August 19, 1924, and more particularly it comprises an improvement upon the construction disclosed and claimed in co-pending application Serial No. 707,044, filed July 18, 1924.

According to the present invention, I have dispensed entirely with the tilting action of the anchor upon the base of the rail. I secure the primary gripping action by the lateral shackling effect of a clamping bolt and secure the secondary or slip responsive gripping action by means of a straight C-clamp which grips the base flange of the rail between the bottom surface of the clamp and the swinging wedge at the top.

I place the transverse bolt diagonally with respect to the rail at an angle of approximately 8° to the normal in order to secure a primary clamping action with a minimum of movement and without imposing an excessive stress upon the bolt. The bolt is set far enough away from the tie that it will not be engaged by the tie and pushed forward.

I place the clamping wedge directly over the bottom jaw of the clamp, depending upon a straight clamping action for the slip responsive or secondary clamping action. Preferably, I make the upper stationary jaw for contacting with the top surface of the base flange, of limited extent, just sufficient in fact, to sustain the lateral shackling pressure, and thereby I am able to position the swinging wedge close to the edge of the rail. The swinging wedge or cam has a cylindrical face, that is, the elements of its active face are parallel to each other, and its axis lies parallel to the elements of its active face and to the top flange surface of the rail. This gives a straight rolling action.

The reduction of the overhang of the clamp decreases the spreading movement on the jaws, increasing the strength of the anchor and decreasing the weight of metal. I have placed the contact of the cam substantially centrally of the lower jaw, thereby securing a more uniform and better friction.

The lower jaw has two flanges along its sides and the contacting area of the lower jaw has been formed into two flat surfaces sufficiently far apart so that the point of contact of the cam may come between them.

This gives a better distribution of the load upon the jaw surfaces.

The angle selected for the hook bolt is such that in the event of slippage of the rail through the grip of the anchor the tension of the lateral shackling will be substantially constant from the time that the anchor is first applied. This bolt is preferably heat treated and the anchor is preferably made of cast steel, although it will be understood that these features are optional.

Since the bolt is placed at an initial angle, when it is tightened up, the tension upon the bolt will remain substantially constant and, hence, the bolt will not be inclined to stretch under a shifting of the rail through the primary grip of the anchor. The angle, however, is small enough to cause a very considerable tension in the bolt when pressure is applied to the face of the anchor.

Another feature to which I wish to call attention is the fact that the webs of the anchor are spread out from the head downward so that they terminate directly at the edges of the jaw surfaces. This results in the maximum strength being developed at the point where the greatest stress is developed.

After this anchor is applied, it becomes a fixed and permanent part of the rail itself and it will not yield within the limits of its strength even under the vibration and pounding to which it is subjected in service.

In order to acquaint those skilled in the art with the manner of constructing and operating my device, I shall now describe in connection with the accompanying drawings a specific embodiment of the invention.

In the drawings:—

Figure 1 is a face view of the anchor shown as applied to the rail, which rail is shown in cross section;

Fig. 2 is a top plan view of the anchor as applied to the rail;

Fig. 3 is a side elevation;

Fig. 4 is a side elevational view of the track showing the means for anchoring the central part of a rail to a plurality of ties against movement in either direction; and

Fig. 5 is a rear elevation of the cam.

The anchor shown in the drawings comprises three main parts: the clamp member 1 which is generally C-shaped, a hook bolt member 2, and a movable wedge member 3,

By means of the bolt 2 and the clamp 1, a lateral shackling action or gripping action is secured upon the base of the rail 4 and by means of the clamp 1 and wedge 3, a vertical clamping action upon the outer flange 5 of the base of the rail 4 is secured.

The clamp member 1 has a pad or contact face 6 for engaging the tie 7, as shown in Fig. 3. The clamp member 1 has a head portion 8 which forms an arched socket, shown in dotted lines in Fig. 1 at 9, for receiving the hub or pintle 10 of the wedge member 3, these parts being held in assembly by means of a pin or rivet 11, which, it will be understood, is not intended to sustain the stress of the vertical clamping action secured by the wedge 3. The head 8 overhangs the pintle or hub 10 and the contacting or cam surface 12 lies in line below said head and hub.

Two webs or flanges 13 and 14 extend from the head down to the bottom of the clamp and merge into two separate jaw surfaces 15 and 16.

These separate jaw surfaces 15 and 16 lie directly below the co-operating cam surface 12 and are disposed symmetrically upon each side of the point of contact, as will be apparent from Fig. 2. The pressure, which is, therefore, exerted upon the base flange 5, is distributed substantially uniformly over the bottom surfaces 15 and 16 and the metal of the clamp is thereby substantially evenly stressed.

The clamp 1 has an upper clamping jaw 17 of relatively short length, as will be apparent from Fig. 1, and this overhangs the top edge of the base flange 5, only enough to hold the clamp well upon said base flange under the lateral shackling action of the bolt 2. The jaws 15 and 16 disposed below the base flange 5, are connected by a web 18, as is apparent from Fig. 3. In like manner, the flanges 13 and 14 are connected by the main body portion of the clamp, which forms a web as indicated at 19, between said rearwardly extending flanges.

The hook bolt 2, which has a hook as indicated at 20, at its outer end for hooking over the base flange 21, extends through an integral sleeve 22 formed on the main body part of the C-clamp 1, between the flanges 13 and 14. This sleeve 22 is set at an angle of approximately 8° and the bolt 2 is set at a like angle so that the first movement of the rail through the grip of the clamp, does not over-stress the bolt 2 and yet secures a clamping action of great value. The bolt 2 is preferably heat treated, and in samples which I have constructed and tested, is made of a diameter of three-quarters of an inch. It is drawn tight by means of the nut 23, which may be a standard nut, such as is used on tracks under present conditions.

I have provided a guiding boss 25 which

projects forwardly from the main body of the clamp 1 and engages the flange 26 of the cam portion 12, so as to afford lateral support for said cam member 3, as the pressure thereupon is increased. Preferably, the cam is set at a very slight angle, such that there is a resulting pressure between the flange 26 of the cam and the guiding boss or projection 25.

The top rear end of the cam 3 is preferably thickened, as indicated at 27 in Fig. 3, for the purpose of strengthening the part which needs to sustain the greatest load and for providing a striking face to be engaged by a hammer or other tool, when the anchor is set in position.

The mode of application and operation of the device is as follows: The swinging wedge or cam 3 is first moved to its furthermost counter-clockwise position, as viewed in Fig. 3, and the clamp 1, without the bolt 2, is applied to the base flange 5. The hook bolt is then passed through the sleeve 22, the hook end 20 passing over the base flange 21, and the nut 23 being tightened up to the desired degree, to fasten the clamp upon the rail. The swinging wedge or cam 3 is then dropped into place, and is driven tight by means of a hammer. Thereafter, pressure coming upon the pad or face 6 tends to push the clamp 1 along the base flange 5, this tendency being initially opposed by the lateral shackling effect of the bolt 2 and the clamp 1, but as the vibration and pounding of the traffic over the rail 4, tends to cause creepage of the rail through the grip of the clamp 1 under the shackling effect of the bolt 2, the cam 3 is tightened, securing a very great pressure upon the base flange 5 and providing a very large holding power.

In samples which I have constructed and tested on 100 pound rails, using a bolt 2 of three-quarter inch diameter and making the clamp and wedge of cast steel, I have found that these samples will uniformly stand pressures up to twelve and one-half tons.

It will be appreciated that the stress upon the clamp 1 is under such circumstances, very high, and it is approximately three times the holding power of the anchor on the rail. The initial shackling effect of the bolt 2 and clamp 1 is dependent upon the tightness of the transverse member 2, the angle at which the bolt 2 is placed and the friction existing between the parts. This lateral shackling action is, however, not the chief holding power of the device. The chief holding power of the device comes through the powerful action of the cam lock 3. It will be noted that the transverse action is exerted in a horizontal direction, and the secondary or chief gripping action operates in a vertical direction.

It is to be understood that a lock washer may be employed under the nut 23 where de-

sired, in accordance with standard railroad practice.

These anchors are preferably made in right and left pattern and go on the outside 5 flange of each rail.

In Fig. 4, I have shown the manner in which the anchors may be used to fasten the central part of a rail against movement. In this case, the central part of the rail is 10 held by means of the two anchors 29 and 30, fastened upon opposite sides of the tie 31, which tie is secured to adjacent ties as by means of a strap 32, which strap is bolted to the ends of the ties 33 and 34, at substantially 15 their neutral axes. The strap 32 does not need to transmit thrust, since it will serve in tension to fasten one tie to the adjacent tie and due to fastening at the neutral axis, that is, substantially the longitudinal axial center 20 of the tie, the pull through the strap 32 is exerted upon the adjacent tie, without a tendency to turn or rotate the same. Thus, the stress of an anchor may readily and cheaply be transmitted, not only to its contacting tie but to an adjacent tie. Obviously, 25 where the rail is anchored against movement in only one direction, the tie which it engages leads the strap to only one adjacent tie.

30 I do not intend to be limited to the details shown or described.

I claim.

1. In an anchor of the class described, a 35 jaw portion for embracing a base flange of a rail, means for holding said jaw portion laterally upon the base flange and a cam having its axis substantially parallel to the top surface of the flange and having a cam surface substantially parallel to its axis.

40 2. In a rail anchor, a clamp for engaging the base flange of a railroad rail, and transverse shackling means for holding said clamp laterally against the rail, said means lying on a diagonal line transversely to the 45 longitudinal axis of the rail and at such an angle that the lateral shackling will be substantially constant from the time that the anchor is first applied to the rail.

3. In a rail anchor, a clamp for engaging 50 the base flange of a railroad rail, and transverse shackling means for holding said clamp against the rail disposed initially in a position which it would have to ultimately assume with the longitudinal shifting of the 55 rail so that the tension on said means will be substantially constant.

4. In an anchor, a C-shaped clamp having 60 a head, a pair of flanges extending from the head along the sides thereof, separate flat base-engaging surfaces formed above the bottom of said flanges and a swinging wedge pivoted to said head and adapted to engage the top surface of the base flange of a rail between said surfaces.

65 5. In an anchor, a C-shaped clamp having

a head, a pair of flanges extending down from the head along the sides thereof, flat base-engaging surfaces connected to said flanges and a cam having a cylindrical cam surface, said cam being pivoted on an axis 70 parallel to the plane of the upper surface of the base and transverse to the longitudinal axis of the rail.

6. In a rail anchor having a frictional rail engaging surface, movable means actuated by the slippage of the rail with respect to said surface for increasing the pressure upon said surface, said means engaging the rail substantially centrally of said frictional rail engaging surface. 75

7. In an anchor of the class described, a C-shaped clamp having a head providing a stationary bearing, a pair of jaw surfaces and a swinging cam having a movable part journalled in said stationary bearing and 80 having an engaging cam surface for engaging the top surface of the base flange of the rail between said jaw surfaces.

8. In a rail anchor, a C-shaped clamp having a head adapted to lie above the base 90 flange of the rail, a body portion, and flanges extending from the head along the outer edges of the body portion and terminating in jaw surfaces adapted to engage the bottom surface of the base flange of the rail, 95 and a swinging cam member pivoted on an axis lying between said rearwardly extending flanges.

9. In an anchor, a C-shaped clamp having 100 opposing engaging surfaces for gripping the top and bottom surfaces of the base flange of a rail, and a shackling hook bolt extending through said clamp for holding the clamp upon the rail, said hook bolt lying at a slight angle to normal on a diagonal line transversely to the longitudinal axis of the rail so that the lateral shackling will be substantially constant from the time the anchor is first applied to the rail. 105

10. In combination, a C-shaped clamp for 110 engaging the top and bottom surfaces of the base flange of a railroad rail, lateral shackling means for holding said clamp upon the rail and means independent of the shackling means for tightening the grip of said clamp 115 upon said rail, said means comprising a cam having a cylindrical cam surface for engaging the top of the base flange of the rail.

11. In combination, a C-shaped clamp, a hook bolt hooked over the opposite base flange of the rail and extending through the body of the clamp, said hook bolt lying at a slight angle to the normal, and a swinging wedge pivoted on the clamp over said bolt. 120

12. In a rail anchor, gripping means for 125 engaging the base flange of the rail and having a tie abutting portion, means actuated by a relative movement between said rail and said gripping means for increasing the grip of said engaging means upon the base 130

flange of the rail, said last means engaging the said rail substantially centrally of said gripping means, and a hollow sleeve integral with the gripping means and disposed immediately below the point of contact between said second means and said rail.

13. In a rail anchor, gripping means for engaging the base flange of the rail and having a tie abutting portion, means actuated by a relative movement between said rail and said gripping means for increasing the grip of said engaging means upon the base

flange of the rail, said last means engaging the said rail substantially centrally of said gripping means, and transverse shackling means for holding said gripping means against the rail disposed initially in a position which it would have to ultimately assume with the longitudinal shifting of the rail.

20 In witness whereof, I hereunto subscribe my name this 16th day of March, 1925.

HERMANN HILL.
